(57) CLAIM

The ornamental design for a beauty instrument, as shown and described.

DESCRIPTION

FIG. 1 is a first perspective view of a beauty instrument showing my new design;
FIG. 2 is a second perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is an enlarged view of the selected portion in FIG. 2. The even length broken lines immediately adjacent to the shaded areas depict the bounds of the claimed design, while all other even length broken lines are directed to environment. In addition, the dot-dash broken lines illustrate enlarged portions of the design. None of the broken lines form part of the claimed design.

1 Claim, 9 Drawing Sheets
